UNITED STATES PATENT OFFICE

2,524,614

EXTRACTOR

Thomas S. Watson, Milwaukee, Wis., assignor to
 Huebsch Manufacturing Company, Milwaukee,
 Wis., a corporation of Wisconsin

Application November 29, 1944, Serial No. 565,763

3 Claims. (Cl. 68—242)

1

The invention relates to compression extractors and more particularly to that type of extractor in which fluid pressure exerted against a flexible diaphragm compresses the material operated upon between said diaphragm and an apertured portion of an enclosing casing to extract liquid from said material. Extractors of this kind have been found to have advantages for extracting water from laundry and for reducing the liquid content of brewery mash, so that the waste mash solids may be used as a feed product, and they may be used in other arts or processes where reduction of the liquid content of a compressible material is desirable.

The object of this invention is to provide a new and improved cover arrangement for extractors of the type above described wherein the cover is fixed and the container is mounted for swinging into an operative covered position or into a loading position and in some instances to a dumping position. With such a construction, the cover may be made of heavy construction to better resist the heavy loads imposed on it.

The invention further consists in the several features hereinafter set forth and more particularly defined by claims at the conclusion hereof.

In the drawings:

Fig. 1 is a front elevation view of a device embodying the invention, parts being shown in section;

Fig. 2 is a side elevation view of the device, parts being broken away and parts being shown in section;

Fig. 3 is a vertical sectional view taken on the line 3—3 of Fig. 2;

Fig. 4 is a detailed vertical sectional view of parts shown in Fig. 3 showing certain modifications.

Referring to Figs. 1 to 3 of the drawings, the extractor comprises a metal walled container 5 having a grooved rim 6 at its top and an opening 7 in its bottom communicating with a pressure supply and exhaust passage 9 in a pipe 19 having a boss 11 secured in fluid-tight engagement with the bottom of the container and having portions pivotally mounted to turn in bearings in frame uprights 12, the container being further supported by side brackets 13 secured to it and to the pipe 10. The exterior closed end of the pipe 19 carries a gear 14 meshing with a segmental gear 15 pivotally mounted on a shaft 16 secured to one of the uprights 12 and connected to an operating link 17 which may be operated manually or by power, for example by an hydraulic cylinder such as shown in my copend-

2

ing application Serial No. 558,255, filed October 11, 1944. The other open end of the pipe 10 is connected by a suitable coupling 18 with a fixed pipe 19 equipped with a valve 20 which controls the inlet of pressure fluid from a pipe 21 and the outlet of said fluid through a pipe 22, said valve being shown as manually operated through a rotatable shaft 23 and a lever 24 connected thereto, though it may be power operated as shown in the aforesaid application. The pipe 21 is connected to a suitable source of pressure fluid, such as water, steam, or compressed air.

A bag 25 of rubber composition or other suitable flexible material fits within the container, 15 and its rim 26 is adapted to fit in a groove in the rim 6 and be clamped therein by a clamping ring 27 secured to the rim 6 by a plurality of screws 28. Usually the cover is secured on top of the ring 27, but in the present instance I have 20 shown the casing extension 29 similar to that of the aforementioned application which includes the ring 27 as its base and at the top of which a cover 30 is mounted in the extracting position of the device. The extension 29 is preferably 25 provided with a plurality of drainage openings 31 and practically doubles the capacity of the extractor without increasing the size of the bag 25 over the usual machines of this type. At its upper end the container is formed with a wall extension 32, spaced from the extension 29 and connected to the container body by a wall 33 to provide a drainage space 34 connected at its lower end to a drain spout fitting 35 which discharges into a fixed funnel 36 secured to a drain pipe 37. The container is preferably round in 35 cross section.

The cover 30 has a rim portion 38 adjacent the rim 44 of the wall extension 32 and a foraminous or apertured metal lining member 40 spaced from but secured to the bottom of the cover by screws (not shown) passing through spacing sleeves 41, said lining fitting over the top of the extension 29. The space between the lining and the cover bottom communicates with the drainage space 34 between the tops of wall and casing extensions. The cover is supported in fixed position by connection of its top with a transverse beam 42 secured at its ends to the uprights 12. The bottom of the cover rim 38 and the member 40 are 45 curved on a radius having as its center the center of oscillation of the container which in the present instance is the center of the pipe 10, and the rims 43 and 44 of the casing are similarly curved, so that the container may be tipped or swung 50 outwardly to one side of the cover to receive or 55

discharge its load. In order that too close a sliding fit between the top of the casing and the cover may not be necessary, and in the case of fine material such as brewery mash to prevent escape of the solids, sealing means are provided between the cover and the casing.

The sealing means includes an endless rubber tube 45 mounted in a recess 46 in the rim 43 and a similar tube 47 mounted in a recess 48 in the rim 44, said tubes when inflated with pressure fluid acting on said rims and the adjacent parts of the cover to prevent escape of fluid from the joints between the cover and the casing. The tubes 45 and 47 are connected by piping 49 with a pipe 50 connected to the pipe 10, so that when the high pressure fluid is introduced into this pipe to raise the bag 25, it will also cause the tubes 45 and 47 to exert a sealing pressure as above described. If desired, the supply of pressure fluid for the seals may be separate from that for the bag and separately controlled.

Where the material operated on consists of fine particles, a filter member 51 may be suitably mounted against the inner wall of the extension 29, and a similar filter member 52 may be secured against the inner side of the lining 40 by a clamping frame 53 secured to the cover as shown in Fig. 4, the same screws (not shown) at the marginal edges of said member 40 and passing through the spacing blocks being used for holding said frame 53.

With the above described construction when the container is tipped to bring its open end outside of the cover as shown in the upper dotted line position in Fig. 1, it is in a loading position. In the case of laundry the clothes carried by a suitable holder are then dropped into the container, and in the case of finely divided material such as brewery mash a spout 54 then registers with the top of the casing. After being loaded, the container is tipped back to the full line position in which its open end registers with the cover 30, and the valve 20 is then opened to allow fluid under pressure from the pipe 21 to flow through the pipes 19 and 10 into the space between the bottom of the container 5 and the bag 25, thus forcing the bag together with its contents upwardly and squeezing or compressing the material between the bag, the container, and the cover 30 so as to force the liquid content of the material out through the holes 31 in the casing 29 and the openings in the cover lining 40 into the space 34 from which it is drained through the spout 35 at the same time some of the fluid pressure passes through pipes 50 and 49 to the tubes 45 and 48 to seal the joints between the top of the casing and the cover. Thereafter, the valve 20 is turned to cut off the pressure fluid from the pipe 21 and open communication with the pipe 22, so that the fluid between the bag and the container 5 may be released. Then the container is swung outwardly from beneath the cover to an unloading position either to the upper dotted line position shown in Fig. 1 in the case of laundry or downwardly to the lower dotted line position in the case of brewery mash or similar materials to a dumping position.

While the use of an apertured cover and extension is preferred, in some instances either the cover or the extension alone may be apertured to

allow the waste liquid to escape from the casing.

I desire it to be understood that this invention is not to be limited to any particular form or arrangement of parts except in so far as such limitations are included in the claims.

What I claim as my invention is:

1. In an apparatus of the character described, the combination of a casing having an open end, a flexible bag mounted in said casing for movement of its body toward said open end, there being a space between said casing and said bag for receiving pressure fluid, a fixed cover for the open end of said casing, means at the bottom of said casing for tiltably supporting said casing so that it may swing into and out of register with said cover, said supporting means having a passage directly connected with the lower end of said casing for the introduction of pressure fluid into the casing below the bag and its exhaustion therefrom, and means for draining waste fluid expelled from the material in the bag.

2. In an extracting apparatus of the character described, the combination of a casing having an open end, a support, said casing having a supporting bearing associated with it at its bottom in the form of pipe pivotally mounted on said support and communicating directly with the lower end of said casing, a flexible bag mounted in said casing for movement of its body toward said open end, a fixed cover registering with the open end of said casing in extracting position, and from which said casing may be swung to loading position, and means for draining waste fluid expelled from the material in the bag, said pipe forming a passage for the introduction of pressure fluid into the casing below the bag and exhausting it therefrom.

3. In an apparatus of the character described, the combination of a casing having an open end, a flexible bag secured to the open end of said casing, there being a space between said bag and said casing for receiving pressure fluid, means for introducing pressure fluid into said space and exhausting it therefrom, an apertured extension for said casing above the connection of said bag to said casing, a fixed cover for the top of said extension and independent thereof, said means for introducing pressure fluid constituting bearing means at the bottom of the casing for pivotal mounting of the casing so that said extension may swing into and out of register with said cover, and means for draining waste fluid expelled from the material in the bag as said bag with its contents is moved by said pressure fluid toward said cover.
